UNITED STATES PATENT OFFICE

2,554,571

FOUNTAIN PAINTBRUSH FOR USE IN
PAINTING CORNER AREAS

Garrett L. Heishman, Sr., Camp Hill, Pa.

Application May 27, 1949, Serial No. 95,788

4 Claims. (Cl. 15—131)

1

This invention relates to fountain paint brush devices, and more particularly, to a fountain brush especially adapted for painting the corner area between a wall and a ceiling for obtaining a sharp separation of color between said wall and ceiling.

A main object of the invention is to provide an improved fountain paint brush device which is simple in construction, easy to use, and operable by one hand.

A further object of the invention is to provide an improved fountain paint brush device which is compact in size, light in weight, and which provides an automatic means for obtaining a sharp separation between a wall and a ceiling, whereby painting of either the wall or the ceiling is greatly facilitated.

Further objects and advantages of the invention will become apparent from the following description and claims, and from the accompanying drawings, wherein:

Figure 1 is a side elevational view of an improved fountain paint brush device constructed in accordance with the present invention;

Figure 2 is a front elevational view of the fountain paint brush device of Figure 1;

Figure 3 is a vertical cross-sectional view taken on line 3—3 of Figure 2;

Figure 4 is a horizontal cross-sectional view taken on line 4—4 of Figure 2.

Referring to the drawings, the fountain paint brush device is designated generally at 11, and comprises a main body portion 12, to the upper front corner portion of which is secured the brush member 14. As shown in Figure 3, the brush device 11 is generally rectangular in contour, said upper front corner portion being cut away to define a sloping surface shown at 15, which is inwardly offset from the vertical front surface of the main portion shown at 16. The brush member 14 comprises a bristle-binding cap 17 which is locked within a recess 18 formed in the upper body portion, opening at the surface 15. Said cap 17 is held in the recess 18 by upper and lower transverse keys 19, 19 engaged in opposing grooves formed in the cap and the adjacent portions of the walls of recess 18. The brush bristles flare upwardly and forwardly and define an acute angle at the top portion of the brush, whereas the lower forward corner of the brush bristles defines an obtuse angle, as viewed in profile in Figures 1 and 3.

Rotatably secured to the side marginal portions of the front surface of the main body 12, and partly housed in vertical grooves 20, 20,

5 formed in said front surface are the vertical rollers 21, 21. Secured in the top surface of said main body in a similar manner are the horizontal rollers 22, 22, extending at right angles to the directions of the rollers 21, 21.

Designated at 23 is a slidably, relatively wide plate member located in a horizontal slot 24 formed in the upper portion of body member 12, and extending substantially over the full width of brush member 14. Plate member 23 carries an upstanding friction locking screw 25 extending through an elongated opening 26 connecting slot 24, to the top of body member 12. The plate member 23 may be adjusted to a position wherein it almost engages the brush member 14 to prevent paint from being spread on a ceiling surface above the brush.

However, the primary function of plate member 23 is to serve as a guide when painting a wall around the molding or door jamb of a door or window, as will be subsequently described.

Pivoted in the upper portion of body 12 at 27 is a rod member 28 carrying at its forward end a transverse horizontal bar 29 overlying the brush 14 subadjacent plate member 23 and acting to limit upward flexure of the bristles of the brush. The position of bar 29 may be adjusted by changing the angular position of rod 28. As shown in Figure 3, the rear end portion of rod member 28 extends through a vertical slot 30 formed in a bowed spring plate 31 secured to the rear surface of body member 12, and threaded on the rod member is a thumb nut 32, enabling the rod 28 to be frictionally locked in a desired position of angular adjustment.

The body member 12 is formed with a paint reservoir 33 provided with a filling spout 34 at the rear wall of the body member, said spout being normally closed off by a plug 35. The upper forward corner of reservoir 33 has a conduit element 36 provided with a flared top funnel member 37 opening into the space subadjacent the brush member 14, as shown in Figure 3.

The lower portion of body member 12 is formed with a horizontal bore 38 in which is axially secured a cylindrical member 39 slightly smaller in diameter than said bore and defining a cylindrical recess therebetween. Slidably fitting over member 39 is a cylindrical cup element 40. Secured to member 39 is a deformable sealing cup 41 slidably and sealingly engaging the inside surface of cup element 40, as shown in Figure 3. The interior of cup element 40 is connected to the bottom of reservoir 33 by a passage 42. Passage 42 contains a check valve 43 adjacent cup ele-

3

ment 40 which allows paint to flow from the reservoir into the cup element but which prevents reverse flow of paint from the cup element to the reservoir. Designed at 44 is a conduit extending through member 39 and body member 12, as shown in Figure 3, said conduit extending through funnel member 37 and being connected, through a check valve 45, to the fountain header 46. The upper portion of header 46 extends through the bristles of brush 14 and is formed with a top upwardly-angled nozzle element 47, directed toward the upper forward corner of the brush, and with a plurality of evenly-spaced, forwardly-directed nozzle elements 48. Check valve 45 allows paint to flow upwardly from conduit 44 to header 46 but prevents reverse flow of paint from the header to said conduit.

Designated at 49 is an arm pivoted to the lower portion of body 12 at 50. The end of cup element 40 has a bracket 51 formed with a vertical slot 52. Arm 49 is formed with a recess 53 receiving bracket 51. A transverse pin 54 extends through this recess, said pin 54 extending also through the slot 52. Arm 49 is thereby movably connected to the end of cup element 40.

Arm 49 is biased outwardly by a coiled spring 55 engaging at one end in a recess 56 formed in the body member 12 and at the other end in a cup defined by a ring member 57 secured to the inner surface of arm 49, as shown in Figure 3. Outward movement of cup element 40 is limited by a depending lip 58 engaged by the upper portion of the end of said cup element.

In operation, paint is drawn into cup element 40 by suction produced by the vacuum developed in said cup element on the release stroke of arm 49. This paint flows through passage 42 and past the check valve 43. On the forward compression stroke of arm 49 the paint is forced through conduit 44 past check valve 45 into the header 46, where the paint is discharged into the brush 14 through the nozzle elements 47 and 48. On release of the arm 49, paint is again drawn into cup member 40 by suction. Surplus paint from brush 14 drips back into the reservoir 33 through the funnel member 37 and return conduit 36. The device 11 is held by the operator against the wall with the rollers 21, 21 in contact with the wall and the rollers 22, 22 in contact with the ceiling. The operator moves the device laterally, alternately compressing and releasing the arm 49. A paint stripe is thus produced on the wall closely adjacent the ceiling, said stripe being sharply defined at the corner joint between the wall and the ceiling. The degree of definition of the stripe may be regulated by adjusting the angular position of the rod 28 by means of the friction nut 32, whereby the abutment bar 29 may be positioned as close as desired to the brush bristles.

It will be apparent from the foregoing description that only one hand is required to manipulate the device, and that waste of paint is held to a minimum.

In painting around a door or window, the plate member 23 is extended to engage the molding or door jamb around the door or window, with sufficient clearance being left for the end of nozzle element 47. To insure sufficient clearance for said nozzle element, plate member 23 may carry a stop flange, such as shown at 23', which is adapted to abut the corner portion of the jamb or molding and prevent the plate member 23 from being excessively extended.

When painting vertical stripes, as at the sides of a door or window, conduit element 36 may be closed off by a suitable plug 36' during the vertical painting strokes to prevent leakage of paint from reservoir 33, while the device is being held in a horizontal position. Said plug may be attached to wall surface 15 by a suitable cord. The plug is inserted in the conduit 36 after brush member 14 has been moistened to a sufficient degree to provide the desired vertical painting stroke. When not in use, the plug 36' may be housed in a suitable recess provided in surface 15 below brush 14.

While a specific embodiment of a fountain paint brush device has been disclosed in the foregoing description, it is to be understood that various modifications within the spirit of the invention may occur to those skilled in the art. Therefore, it is intended that no limitations be placed on the invention except as defined by the scope of the appended claims.

What is claimed is:

1. A fountain brush device of the character described comprising a body member having vertical rollers journaled at the forward vertical side thereof and horizontal rollers journaled at the top thereof extending at right angles to the plane of the vertical rollers, said body member carrying an upwardly and forwardly-directed brush at its forward upper corner, a paint reservoir carried by said body member, nozzle means located in said brush, conduit means connecting said reservoir and said nozzle means, and manually-operated means for forcing paint from the reservoir into said conduit means.

2. A fountain brush device of the character described comprising a body member having a generally rectangular profile and having vertical rollers journaled at the forward vertical side thereof and horizontal rollers journaled at the top thereof extending at right angles to the plane of the vertical rollers, said body member being beveled and inwardly offset at its forward upper corner and carrying an upwardly and forwardly-directed brush at said forward upper corner, a paint reservoir carried by said body member, nozzle means located in said brush, conduit means connecting said reservoir and said nozzle means, and manually-operated means for forcing paint from the reservoir into said conduit means, said body member being formed with a return passage connecting said forward upper corner and said reservoir.

3. A fountain brush device of the character described comprising a body member having a generally rectangular profile and having vertical rollers journaled at the forward vertical side thereof and horizontal rollers journaled at the top thereof extending at right angles to the plane of the vertical rollers, said body member being beveled and inwardly offset at its forward upper corner and carrying an upwardly and forwardly-directed brush at said forward upper corner, a paint reservoir carried by said body member, nozzle means located in said brush, conduit means connecting said reservoir and said nozzle means, a check valve in said conduit means allowing paint to flow to said nozzle means but preventing reverse flow thereof, and manually-operated means for forcing paint from the reservoir into said conduit means, said body member being formed with a return passage connecting said forward upper corner and said reservoir, and said manually-operated means comprising a collapsible cylinder, spring means biasing said cylinder

toward expanded position, the cylinder being connected to said conduit means, and the body member being formed with a passage connecting the reservoir to said cylinder, said passage being provided with a check valve allowing paint to flow therethrough into the cylinder but preventing reverse flow thereof.

4. A fountain brush device of the character described comprising a body member, an upwardly and forwardly-directed brush positioned at the forward upper corner of said body member and carried by the latter, a paint reservoir carried by said body member, nozzle means located in said brush and connected to said reservoir, manually operated means for forcing paint from the reservoir to said nozzle means, and roller means on

5 said body member for spacing and moving said body member over the surface to be painted.
